UNITED STATES PATENT OFFICE.

SAMUEL TULLY WILLSON, OF BROOKLYN, NEW YORK.

BURNER-HEAD.

1,289,992.

Specification of Letters Patent. Patented Dec. 31, 1918.

Application filed February 6, 1916. Serial No. 146,991.

To all whom it may concern:

Be it known that I, SAMUEL TULLY WILLSON, a citizen of the United States, residing at Brooklyn, in the county of Kings and 5 State of New York, have invented certain new and useful Improvements in Burner-Heads; and I do hereby declare the following to be a full, clear, and exact description of the invention, such as will enable others 10 skilled in the art to which it appertains to make, and use the same.

This invention relates to burner heads for gaseous fuel, and it has for an object, to provide a burner head which affords great 15 concentration of heat.

Another object of this invention is to provide a burner head in which rapid flame propagation of gaseous fuel occurs.

A further object of this invention is the 20 provision of a burner head for gaseous fuel in which combustion of the fuel produces a short flame of intense heat.

A further object of this invention is a 25 provision of a burner head for gaseous fuel in which the flame plate is used, said flame plate being so formed as to permit partial or complete combustion of a fuel within apertures formed therein.

A further object of this invention is a 30 provision of a flame plate for burner heads having apertures formed therein, in which combustion of a gaseous fuel occurs.

A further object of this invention is the 35 provision of a plate of refractory material having apertures formed therein, in which combustion of a gaseous fuel occurs, said apertures being so arranged as to preclude the liability to back fire.

Further objects will be apparent from the 40 following specification, appended claims and drawings, in which—

Figure 1 is a plan view of the burner head, and

Fig. 2 is a vertical cross section there- 45 through, as on the line 2—2 of Fig. 1.

This burner head provides for the genera- 50 tion of intense heat in limited space, and this is accomplished by rapid flame propagation in a flame plate which is of refractory material. This flame plate is provided with apertures in which partial combustion of a gaseous fuel occurs and these apertures are so formed as to cause the gaseous fuel to be admitted into them at their base at such 55 velocities, dependent on the nature of the gaseous fuel, to cause rapid combustion of

the fuel and also to prevent back fire into the distributing chamber. This refractory head, upon becoming heated to incandescence by the combustion of the gaseous fuel, within its confines throws off an intense radiant heat and, as will be disclosed in the following specification, this flame plate may be placed in close proximity to a surface being heated.

Referring to the drawings (more especially Fig. 2) in which the several features of this invention are clearly shown, 10 indicates a "flame plate" having apertures 11 formed therein which have a diameter equal to approximately one-half of their length. This flame plate is supported by the side wall 12 rising above the partition 13. Extending below the partition 13 is the downwardly tapering wall 14 to form a distribut- 75 ing chamber 15. The foregoing comprises what may be termed the burner head, and this may be supported by the nipple 16, elbow 17 and supply pipe 18 through which the gaseous fuel may be fed to the distribut- 80 ing chamber 15.

The apertures 11 in the flame plate 10 are arranged in correspondingly spaced relationship by the webs 20 to distribute the heat caused by the combustion of a gaseous 85 fuel therein throughout said flame plate. This flame plate is of refractory material so that radiant heat is thrown off when this plate has been heated to incandescence, but the side wall 12, partition 13 and shell 14 90 are of metal which transfers the heat by conduction toward the cooler portions to maintain the temperature of these parts below ignition point of the gas. These apertures are of such predetermined cross sec- 95 tional area as to properly permit combustion of a gaseous fuel therein.

The partition 13 has passages 19 formed therein which communicate with the lower portions of the apertures 11 and these passages are preferably concentric with the apertures 11. The diameters of the passages 19 are approximately one-third of the diameters of the apertures 11, but proportion- 105 ment may be varied in the burner head as used for gases of different characteristics. These passages form jets which admit the gaseous fuel into the apertures 11 in ve- locities equal to or greater than the rate of flame propagation so as to prevent back- 110 fire into the distributing chamber.

As the gaseous fuel is fed through the pipe

18 properly mixed with the desired volumes of air and at the desired velocity, it will pass into the distributing chamber 15, from whence it passes through the passages 19 5 into the apertures 11. Combustion of the gas occurs within these apertures, so that it is seen that the burner head may be placed in close proximity to a surface to be heated and by the combustion of the gas the side walls 10 of the apertures 11 are heated to incandescence, at which time an intense radiant heat is thrown off. The apertures 11 are proportioned to allow gaseous fuel being partially consumed therein, having the apex 15 of the flame occur slightly above the upper surface of the flame plate, and as the gaseous fuel is fed through the passages 19, a chilling action is had which serves to prevent the partition 13 from becoming heated 20 to such a degree as to ignite the gas and likewise the lower face of the flame plate is also maintained at a degree of heat below the ignition point.

It is apparent to those familiar with this 25 type of apparatus, that the number of apertures in the flame plate may be increased or decreased as desired but in each instance, the resultant action will be similar.

Having thus described this invention, I 30 claim:

1. A gas burner comprising a head having a distributing chamber formed therein, a partition in said head, a refractory flame plate carried by said partition, said refractory flame plate having apertures therein in which combustion of a gaseous fuel occurs to heat said refractory flame plate to incandescence and thereby creating radiant heat, said partition having passages formed there- 35 in communicating with said apertures, said passages being proportioned to admit gaseous fuel into said apertures at a velocity to prevent back fire into the mixing chamber and said passages serving to maintain the 40 temperature of said partition below the ignition point.

2. In a burner head of the class described, a fitting, a partition across said fitting to form a distributing chamber, said partition 50 having passages therein which communicate with said distributing chamber, a side wall rising above said partition, and a flame plate

of refractory material having apertures formed therein which register with the passages in the partition, but having said apertures of a cross sectional area increased relatively to the cross-sectional area of said passages, carried by said partition within said side wall. 55

3. In a burner head, a fitting, a side wall 60 formed by said fitting, a partition across said fitting forming a distributing chamber, said partition having passages formed therein which communicate with said distributing chamber, said passages having reduced cross-sectional areas to form jets for gaseous fluid passing from said distributing chamber, a flame plate of refractory material carried by said partition within said side wall, said flame plate having apertures formed therein 65 which register with said passages having said apertures of increased cross-sectional area than the area of said passages, and having enlarged webs of the refractory material comprising said flame plate formed between 70 75 said apertures so that in the combustion of a gaseous fuel within said apertures, these webs and the adjacent portions of said flame plate are heated to a degree of incandescence to thereby form radiant heat. 80

4. In a burner head of the class described, a fitting, a partition within said fitting forming a distributing chamber, a side wall surrounding said partition and rising above the level thereof, a flame plate of refractory material carried by said partition within said side wall, said partition having reduced passages formed therein through which volumes of gaseous fuel are discharged from the distributing chamber, said fitting 85 and partition being of a heat conducting material to thereby conduct the imparted heat and dissipate the same, said refractory flame plate having apertures formed therein which register with the passages in said partition, and which are of relatively larger cross-sectional area than the area of said passages, and said partition and flame plate having the passages and apertures so formed therein as to have enlarged webs of the refractory material between said apertures. 95 100

In testimony whereof I affix my signature.

SAMUEL TULLY WILLSON.
